UNITED STATES PATENT OFFICE.

SAMUEL N. MAXAM, OF SHELBURNE FALLS, MASSACHUSETTS.

IMPROVEMENT IN SINKS.

Specification forming part of Letters Patent No. 37,454, dated January 20, 1863.

To all whom it may concern:

Be it known that I, SAMUEL N. MAXAM, of Shelburne Falls, in the county of Franklin and State of Massachusetts, have invented a new and useful Improvement in Sinks; and I do hereby declare that the following is a full and exact description thereof, reference being had to the accompanying drawings, and to the letters of reference marked thereon, the said drawings making a part of this specification, in which—

Figure 1 is a perspective view, as is also Fig. 2.

Letter A represents the top slide-grate, moving lengthwise in a groove cast in the sink, having wooden bars (marked F) placed transversely upon it, or raised slightly above it, supported on posts cast upon it, the wooden bars F being used for supporting dishes and vessels while draining into the sink beneath.

Letter B represents the lower slide-grate, moving lengthwise in a groove cast in the sink underneath the groove in which the top slide-grate, A, moves, and is for receiving the dishes

and vessels drained upon top slide-grate, A, when dried.

The letter C represents a circular basin for holding water, cast in the sink.

The letter D represents a movable wash-bowl, moving upon the yoke marked E, and sliding on the rod marked G, in such a manner that it may be placed in and rest upon the bottom of the sink, or by means of the yoke E may be removed and placed outside of and at a convenient distance from the sink.

What I claim as my invention, and desire to secure by Letters Patent, is—

The combination and arrangement of the top slide-grate, A, with the transverse wooden bars F, and the lower slide-grate, B, and the basin C, and the movable wash-bowl D, resting in and upon the yoke E, and sliding upon the rod G, for the purposes of a sink, and as above set forth.

SAMUEL N. MAXAM.
